HAIR CURLER

Walter H. Hermsdorf, Chicago, Ill., assignor to
Chain Store Products Corporation, Chicago,
Ill., a corporation of Delaware

Application April 14, 1939, Serial No. 267,740

7 Claims. (Cl. 132—33)

This invention relates to improvements in hair curling devices and refers specifically to a device upon which a strand of hair may conveniently be curled, and in conjunction with which a hair pin or fastener may be automatically positioned to hold the strand in curled condition.

The objects and advantages of my invention will be apparent from the accompanying drawings and following detailed description.

In the drawings, Fig. 1 is a side elevational view of my hair curling device.

Fig. 2 is a top plan view of the device shown in Fig. 1.

Fig. 3 is an enlarged, longitudinal sectional view of the curling device.

Fig. 4 is a transverse sectional view taken on line 4—4 of Fig. 3.

Fig. 5 is a transverse sectional view taken on line 5—5 of Fig. 3.

Fig. 6 is a side elevational view, parts being broken away and parts being shown in section, of my curler with a strand of hair wound thereon.

Fig. 7 is a side elevational view of a modification of my invention.

Fig. 8 is a top plan view of the device shown in Fig. 7.

Fig. 9 is a longitudinal sectional view of the device with a hairpin mounted thereon.

Fig. 10 is a view similar to Fig. 9 showing the hairpin moved to operative position.

Fig. 11 is a transverse sectional view taken on line 11—11 of Fig. 7.

Fig. 12 is a sectional view taken on line 12—12 of Fig. 7.

Fig. 13 is a side elevational view, parts being shown in section of another modification of my invention.

Fig. 14 is a sectional view taken on line 14—14 of Fig. 13.

Fig. 15 is a view similar to that shown in Fig. 14, with a strand of hair wound thereon.

Referring in detail to the drawings, 1 indicates a hair curler embodying the concepts of my invention. The curler 1 comprises two members designated 2 and 3 which are rotatable relative to each other.

The member 2 comprises a rod 4 which carries at one end an annular knob 5, and at the opposite end an annular collar 6 is rigidly mounted on said rod. A tubular member 7 is rigidly positioned on the exterior of collar 6 and is provided with diametrically disposed elongated slots 8 which open toward the free end of the member 7, the edges of the slots being relieved, as at 9 to provide a clothespin-like end. A leaf spring 10 is positioned at one end between the collar 6 and tubular member 7, said spring being positioned within the member 7 and extending toward its free end where the spring is bent, as at 11.

The member 3 is of hollow construction and embraces rod 4 between knob 5 and collar 6, the member 3 serving as a bearing for rod 4 whereby said rod may be rotated within the hollow member 3. A sleeve 12 is rigidly mounted upon member 3, or, if desired, may be formed integral with said member. The sleeve 12 is provided with a longitudinal slot 13 which extends substantially parallel to the axis of rod 4. A ring 14 is rigidly mounted upon or may be formed integral with sleeve 12, said ring being provided with an opening 15 into which slot 13 opens. A portion of ring 14, at a point in alignment with slot 13, overhangs a portion of the opening 15, the upper contour of the overhanging portion 16 being curved to conform substantially with the crimps 16' of a hairpin 17, the hairpin shown being of the conventional "bobby-pin" type. One edge of the overhanging portion 16 is curved, as shown best at 16" in Fig. 2. One defining edge of slot 13 adjacent opening 15 is angularly disposed, as shown at 18 in Figs. 1 and 2, to widen the slot adjacent the ring.

In utilizing the curler 1, the pin 17 is positioned on the member 3 with its legs, adjacent their ends, embracing the overhanging portion 16 of the ring. The longitudinal axis of the pin will thereby be disposed parallel to slot 13. The tension of the pin will hold the pin in place, assisted by the registration of the curved top of the overhang 16 and the crimp 16'. The end of the lower leg 19 rests upon shoulder 20, formed upon the end of member 3, which is flush with the surface of tube 7.

The end of a strand of hair 21 is then inserted in slots 8 through the ends of said slots, thereby displacing spring 10 and in turn being clamped by said spring. The member 3 is then grasped by one hand of the user and held firmly while the knob 5 is rotated by the user's other hand thereby wrapping or winding the strand of hair 21 in cylindrical fashion upon tube 7. It is preferable that the hair be tightly wound upon the tube so as to more neatly set the hair. The winding is continued until substantially the entire length of the strand is wound upon the tube, bringing the tube closely adjacent the scalp of the user.

The pin 17 is then moved longitudinally along slot 13, the lower leg passing beneath the cylindrically coiled hair. During this operation, the hair prevents one end of the pin from moving laterally, and the opposite end, the U-bend, is confined and guided by the walls of slot 13. However, when the U-bend reaches the tapered wall 18, one side of the U-bend being unconfined by the slot wall moves laterally into the opening 15 thereby disengaging the pin from the curler. This lateral movement is caused primarily by the increased tension of the pin as

the U-bend approaches the overhang 16. If desired, the top of the overhang may be sloped slightly to assist this movement. However, the lateral movement will occur whether the member 16 is sloped or not since it is substantially impossible, with the U-bend unguided as it is at this point, to push the pin forwardly in a theoretically straight line. If the pin 17 is still in engagement when the U-bend reaches the overhanging member 16, the curved edge 16" of said overhanging member will deflect the pin therefrom.

The release of the pin by the curler leaves the pin in clamping position upon the cylindrical coil of hair which may be removed together with the retaining pin from the tubular end 7.

It is of decided advantage to clamp the coil of hair by the pin as close to the scalp as possible. By virtue of the fact that the members 2 and 3 are freely rotatable relative to each other, and that the bottom leg 19 of the pin can be moved longitudinally under the coil at any position of the tubular member 7, this position of the pin with respect to the coil and scalp is made possible.

Referring particularly to Figs. 7, 8, 9, 10, 11 and 12, a modification of my invention is shown wherein 22 indicates a tubular member which is rotatably positioned in a tubular sleeve 23. The tubular member 22 is provided, adjacent one end, with diametrically opposite slots 24 similar to the end 7 of member 2. A spring, not shown, similar to spring 10, may be positioned within member 22. A plug 25 is inserted in, and rigidly connected to, one end of member 22, said plug carrying a knurled head 26. Sleeve 23 embraces member 22 and an end of said sleeve is turned inwardly, as at 27, between the end of member 22 and head 26, whereby said sleeve is maintained in desired position upon member 22. It can readily be seen that rotary movement of the knurled head 26, rotates member 22 with respect to sleeve 23.

Sleeve 23 is provided with an elongated slot 28 which is parallel to the axes of sleeve 23 and member 22. Adjacent the open end of slot 28, a defining wall of said slot is relieved or tapered, as shown best at 29 in Fig. 8. A member 30 is riveted or otherwise secured to sleeve 23 adjacent the mouth of slot 28, said member carrying a U-shaped spring 31 which projects from the end of said sleeve. The two legs 32 and 33 of the U-shaped spring project at right angles to the axis of slot 28 and project across the mouth of said slot, as shown best in Figs. 8 and 11.

In utilizing this form of my invention, a strand of hair, not shown, is wound around member 22 similar to the manner hereinbefore described in conjunction with member 2. A hairpin 34 having a U-bend 35 and legs 36 and 37 is positioned in slot 28 with its legs embracing the legs 32 and 33 of the spring 31. Of course, the hairpin 34 may be positioned on sleeve 23 before the hair is wound upon member 22, this being the preferable method of operation. It can readily be seen that the legs 36 and 37 are held apart by the spring 31 so that when pin 34 is moved axially along member 22, legs 37 moves under the coil of hair carried on said member and leg 36 moves therewith. As the pin 34 is thus moved, the legs 36 and 37 increase their tension upon legs 32 and 33 tending to squeeze said latter legs together and permitting the upper leg 36 of the pin 34 to descend upon the coil of hair.

It will be noted that the lower leg 32 of spring

31 projects beyond leg 33 toward slot 28. This permits the lower leg 37 of the pin 34 which is longer than the upper leg 36 thereof to be conveniently engaged beneath the leg 32. In addition, the lower leg 32 of spring 31 is curved, as shown at 38 in Fig. 8, so that when U-bend 35 of the pin 34 reaches the spring member 31, the U-bend 35 contacts the curve 38 of the lower leg 32 and is deflected to edge 29 thereby permitting the disengagement of pin 34 from the curler. The hair engaged or clamped by the hairpin may then be slid from the member 22 as a curl.

Referring particularly to Figs. 13, 14 and 15, another modification of my invention is shown, as curler 39. Curler 39 functions in a manner similar to the curler shown in Figs. 7 to 12 inclusive. Curler 39 comprises an exterior or sleeve portion 40 which embraces a tubular member 41. Similar to the tubular member 22, member 41 is provided with diametrically opposite elongated slots 42 which are adapted to receive the ends of the strand of hair to be curled. One end of the tubular member 41 is provided with an annular flange 43 into which a cup-like member 44 is adapted to be removably positioned, the member 44 being constructed of a transparent resin or other similar transparent material. A partition 45 is disposed intermediate the length of the tubular member 41 whereby a compartment is formed for spare hairpins 46 which are observable through the transparent closure 44.

The opposite end of the tubular member 41 is provided with circumferentially spaced parallel ribs 47. It can readily be seen, by reference to Fig. 15, that when hair 48 is wound around the ribbed end of the tubular member 41, spaces 49 will be provided between the hair and the tubular wall of the member 41. A spring 50, similar in construction to spring 31 is mounted upon the sleeve 40 and said sleeve is provided with a guide slot 51 similar to slot 28. A hairpin 52 is adapted to be positioned in slot 51 with the legs of the pin embracing the spring 50. When the hair 48 is wound about the tubular member 41 the hairpin 52 is moved along slot 51 so as to insert the lower leg of the hairpin in a space 49 and the upper leg of the hairpin above the hair. When the U-bend 53 of the hairpin 52 reaches the spring 50 it is deflected thereby and the hairpin slips laterally from the spring, permitting the legs of the hairpin to grasp the coiled hair. The coil of hair 48, held by the hairpin, may then be removed from the tubular member.

I claim as my invention:

1. A hair curling device comprising, an outer sleeve-like member, an inner member, said inner member projecting beyond an end of said outer member, means for winding a strand of hair in coil fashion upon the projecting portion of said inner member, and a lug upon said outer member for carrying a hairpin thereon, said outer member being rotatable a sufficient degree relative to said inner member to move said hairpin to any desired circumferential position relative to said inner member after the coil of hair has been wound upon said inner member, said lug being arranged and constructed to spread the legs of the hairpin and to maintain said legs in spread relationship during longitudinal movement of said hairpin relative to said lug and to direct one leg of the hairpin between said inner member and said coil of hair during said longitudinal movement.

2. A hair curling device comprising, an outer

sleeve-like member, an inner member, said inner member projecting beyond an end of said outer member, means for winding a strand of hair in coil fashion upon the projecting portion of said inner member, and a lug upon said outer member for releasably carrying a hairpin thereupon, said outer member being rotatable a sufficient degree relative to said inner member so that said hairpin can clamp said coiled hair at any desired circumferential position relative to said inner member after the coil of hair has been wound upon said inner member, said lug being arranged and constructed to spread the legs of the hairpin and to maintain said legs in spread relation during longitudinal movement of said hairpin relative to said lug and to direct one leg of the hairpin under said coil of hair during said longitudinal movement, said lug also being arranged and constructed to permit release of the hairpin therefrom at the end of its longitudinal movement.

3. A hair curling device comprising, an outer sleeve-like member, an inner member, said inner member projecting beyond an end of said outer member, means for winding a strand of hair in coil fashion upon the projecting portion of said inner member, a lug upon said outer member for releasably carrying a hairpin thereupon, said outer member being rotatable a sufficient degree relative to said inner member so that said hairpin can clamp said coiled hair at any desired circumferential position relative to said inner member after the coil of hair has been wound upon said inner member, said lug being arranged and constructed to spread the legs of the hairpin and to maintain said legs in spread relation during longitudinal movement of said hairpin relative to said lug and to direct one leg of the hairpin under said coil of hair during said longitudinal movement, means for releasing said hairpin from said outer member to clamp said coil of hair in said hairpin, and means for guiding said hairpin in a substantially straight line parallel to the axis of said projecting inner member for a major portion of the movement of the hairpin.

4. A hair curling device comprising, an outer member, an inner member which projects beyond an end of said outer member, means for winding a strand of hair into a coil upon the projecting portion of said inner member, a lug carried by said outer member, said lug projecting substantially parallel to and spaced from the surface of said outer member, said lug being adapted to carry a hairpin with its legs embracing and spaced apart by said lug, said outer member being rotatable a sufficient degree relative to said inner member so that said hairpin can clamp said coiled hair at any desired circumferential position relative to said inner member after the coil of hair has been wound upon said inner member, said hairpin being adapted to be moved longitudinally from said outer member to said inner member, said lug being arranged to direct one leg of said hairpin between the coil of hair and the outer surface of the inner member during said movement, said outer member being provided with means permitting said hairpin to be released from said lug when the U-bend of the hairpin is moved to a position adjacent said lug.

5. A hair curling device comprising, an outer sleeve-like member and an inner member which projects beyond an end of said outer member, said outer member being provided with an elongated slot adapted to serve as a guide for a hairpin, a lug projecting over a portion of said slot adjacent one end of said slot, one wall defining said slot receding away from said lug, means for winding a strand of hair on said inner member, the lug on said outer member being adapted to carry a hairpin the legs of which embrace said lug, said outer member being rotatable relative to said inner member to move said hairpin to any desired circumferential position relative to said inner member after the coil of hair has been wound upon said inner member, said hairpin being movable longitudinally of said slot into clamping engagement with said coiled hair, the legs of said hairpin being engaged with said lug during said movement of said hairpin until the U-bend of said hairpin reaches a position opposite the receding wall of the slot whereupon said hairpin can move laterally and become disengaged from said lug.

6. A hair curling device comprising, an outer sleeve-like member, an inner member, said inner member projecting beyond an end of said outer member, means for winding a strand of hair in coil fashion upon the projecting portion of said inner member, and a lug upon said outer member for releasably carrying a hairpin thereupon, said outer member being sufficiently rotatable relative to said inner member that said hairpin can clamp said coiled hair at any desired circumferential position relative to said inner member after the coil of hair has been wound upon said inner member, said lug having resilient legs arranged to spread the legs of the hairpin and to maintain said legs in spread relation during longitudinal movement of said hairpin relative to said lug and to direct one leg of the hairpin under said coil of hair during said longitudinal movement, said lug also being arranged to permit release of the hairpin at the end of its longitudinal movement.

7. A hair curling device comprising, an outer sleeve-like member, an inner member, said inner member projecting beyond an end of said outer member, means for winding a strand of hair in coil fashion upon the projecting portion of said inner member, and a lug upon said outer member for releasably carrying a hairpin thereupon, said outer member being rotatable a sufficient degree relative to said inner member so that said hairpin can clamp said coiled hair at any desired circumferential position relative to said inner member after the coil of hair has been wound upon said inner member, said lug having resilient legs arranged to spread the legs of the hairpin and to maintain said legs in spread relation during longitudinal movement of said hairpin relative to said lug and to direct one leg of the hairpin under said coil of hair during said longitudinal movement, and means for guiding said hairpin in a substantially straight line parallel to the axis of said inner member for a major portion of said movement of the hairpin, said lug also being arranged to permit release of the hairpin at the end of its longitudinal movement.

WALTER H. HERMSDORF,
